UNITED STATES PATENT OFFICE.

ALBERT HARGRAVES, OF AKRON, OHIO, ASSIGNOR TO PROEHL TIRE AND RUBBER COMPANY, OF CHICAGO, ILLINOIS, A CORPORATION OF ILLINOIS.

DESIGN FOR A PNEUMATIC TIRE.

54,318.

Specification for Design.

Patented Dec. 23, 1919.

Application filed September 24, 1919. Serial No. 326,083. Term of patent 14 years.

To all whom it may concern:

Be it known that I, ALBERT HARGRAVES, a citizen of the United States, residing at Akron, in the county of Summit, State of Ohio, have invented a new, original, and ornamental Design for Pneumatic Tires, of which the following is a specification, reference being had to the corresponding drawings, forming a part thereof.

In the drawings, Figure 1 is a plan view of a portion of a tire showing my new design.

Fig. 2 is a cross section on the line 2—2 of Fig. 1.

I claim:

The ornamental design for a pneumatic tire as shown.

ALBERT HARGRAVES.
